(57) **CLAIM**

The ornamental design for a fan as shown and described.

DESCRIPTION

FIG. 1 is a front, right and top perspective view of a fan showing my new design;

FIG. 2 is a rear, left and bottom perspective view thereof;

FIG. 3 is a front elevational view thereof;

FIG. 4 is a rear elevational view thereof;

FIG. 5 is a right view thereof;

FIG. 6 is a left view thereof;

FIG. 7 is a top plan view thereof;

FIG. 8 is a bottom plan view thereof;

FIG. 9 is another front, right and top perspective view thereof, showing the fan in a tilted configuration;

FIG. 10 is a rear, right and bottom perspective thereof, showing the hook in an extended configuration and the fan in a tilted configuration; and,

FIG. 11 is an enlarged view of a portion labeled as 11 on FIG. 1.

The long dash-short dash broken lines depict enlargement boundaries that form no part of the claim. The evenly broken lines illustrate portions of the article that form no part of the claimed design.
